UNITED STATES PATENT OFFICE.

NEIL S. LINCOLN, OF DETROIT, MICHIGAN.

DESIGN FOR AN OIL GAUGE.

Application filed August 13, 1928. Serial No. 27,800. Term of patent 7 years.

To all whom it may concern:

Be it known that I, NEIL S. LINCOLN, a citizen of the United States, residing at Detroit, in the county of Wayne and State of Michigan, have invented a new, original, and ornamental Design for Oil Gauges, of which the following is a specification, reference being had to the accompanying drawing, forming part thereof.

Fig. 1 of the drawing is a front elevation of an oil gauge, showing my new design; and indicates in dotted lines an automobile instru-

ment-board with which my oil gauge is associated. Fig. 2 is a side elevation of the oil gauge.

I claim:

The ornamental design for an oil gauge, as shown.

In witness whereof, I have hereunto set my hand at Connersville, Indiana, this tenth day of August, A. D. one thousand nine hundred and twenty-eight.

NEIL S. LINCOLN.
